(57) **CLAIM**

The ornamental design for a disinfection device, as shown and described.

DESCRIPTION

FIG. 1 is a top front right perspective view of a disinfection device, showing the new design in a lid closed configuration; FIG. 2 is a top front left perspective view thereof; FIG. 3 is a top rear left perspective view thereof; FIG. 4 is a top rear right perspective view thereof; FIG. 5 is a bottom front right perspective view thereof; FIG. 6 is a bottom front left perspective view thereof; FIG. 7 is a bottom rear left perspective view thereof; FIG. 8 is a bottom rear right perspective view thereof; FIG. 9 is a front view thereof; FIG. 10 is a rear view thereof; FIG. 11 is a left side view thereof; FIG. 12 is a right side view thereof; FIG. 13 is a top view thereof; FIG. 14 is a bottom view thereof;

FIG. 15 is a top front right perspective view of the disinfection device, showing the new design in a lid open configuration; FIG. 16 is a top front left perspective view thereof; FIG. 17 is a top rear left perspective view thereof; FIG. 18 is a top rear right perspective view thereof; FIG. 19 is a bottom front right perspective view thereof; FIG. 20 is a bottom front left perspective view thereof; FIG. 21 is a bottom rear left perspective view thereof; FIG. 22 is a bottom rear right perspective view thereof; FIG. 23 is a front view thereof; FIG. 24 is a rear view thereof; FIG. 25 is a left side view thereof; FIG. 26 is a right side view thereof; FIG. 27 is a top view thereof; and, FIG. 28 is a bottom view thereof.

Broken lines in the figures show portions of the disinfection device that form no part of the claimed design.

1 Claim, 23 Drawing Sheets
